United States Patent Office

Des. 214,660
Patented July 15, 1969

214,660

CAP

Endre Szombathy, 37 W. 20th St.,
New York, N.Y. 10011

Filed Aug. 26, 1968, Ser. No. 13,275

Term of patent 14 years

Int. Cl. D2—03

U.S. Cl. D2—248

FIG. 1 is a front perspective view of a cap showing my new design;

FIG. 2 is an enlarged front elevational view thereof;

FIG. 3 is a top plan view of FIG. 1;

FIG. 4 is a rear elevational view thereof; and

FIG. 5 is a side elevational view.

I claim:

The ornamental design for a cap, substantially as shown.
